UNITED STATES PATENT OFFICE

JOSEPH JEROME CAUDLE, OF RICHMOND, VIRGINIA, ASSIGNOR TO BRITISH-AMERICAN
TOBACCO COMPANY, LIMITED, OF LONDON, ENGLAND, A CORPORATION OF GREAT
BRITAIN

TOBACCO STEMMING MACHINE

Application filed November 22, 1928. Serial No. 321,058.

This invention relates to a stemming machine for the purpose of separating the stem of a leaf from the web or body portion by drawing the stem outward from the web. It pertains more particularly to the stemming of tobacco leaves and has a wide use in the tobacco industry because the stems of the leaf being made of a woody fibre are objectionable in smoking or chewing tobaccos.

10 An object of this invention is the provision of a machine which will automatically remove the stem of a tobacco leaf from the web thereof without breaking off the stem and thus leaving part of it in the web or lamina. 15 Another object is to provide a machine which will automatically feed the leaves to the stemming means and perform a continuous operation of stemming successive leaves.

20 A further object is to provide for the stemming of leaves of various lengths and thicknesses without readjustment of the mechanism or replacement of parts thereof.

25 And still another object is to provide for the gripping of the leaf in suitable stripping members and removal therefrom without breaking or tearing the body of the leaf and thus producing an excessive amount of scrap or waste material.

30 This machine embraces in its generic features a cardcloth-covered revolving drum above which is arranged to cooperate therewith an endless linearly moving cardcloth belt. A feeding device is adapted to feed tobacco leaves between said drum and said belt in such manner that part of the body of the leaf will be gripped therebetween while the butt-end of the stem will project slightly beyond the drum and belt. The leaves are carried forward by the rotation of the drum, and when in proper position, the projecting stem butts are gripped by a rocking gripper device which rocks or swings back and forth at right angles to the drum, and in timed relation therewith. As the gripper seizes a projecting stem and starts its rocking or swinging movement away from the drum, it draws the stem from the leaf, leaving the stemmed tobacco between the drum and the cardcloth belt. At the end of its movement away from the drum the gripper is opened and dis-

charges the stem. The stemmed tobacco is carried forward around the cardcloth drum to a point of discharge where the tobacco is gently removed from the cardcloth drum without excessive scrap and is discharged 55 into a suitable container or conveyer.

In the accompanying drawings forming a part of this specification wherein similar reference characters refer to similar parts throughout the several views, I have illustrated a machine constructed in accordance with the principles of the present invention.

Fig. 1 is a side elevation of the machine with part of the gripper mechanism and part of the stationary cam stop cut away; 65

Fig. 2 is an end view taken from the right side of Fig. 1;

Fig. 3 is a sectional view taken on line 3—3 of Fig. 1;

Fig. 4 is a fragmentary side elevation illustrating one type of gripping means; 70

Fig. 5 is a fragmentary top plan view with the carding belt removed.

The framework of the machine is designed to support the various movable elements, and comprises a base portion made up of vertical members 1, 1^a, 1^b, 1^c, joined together and braced by transverse cross members 2, 2^a, 2^b, 2^c, 2^d, 2^e. 75

A revolving drum 3 is keyed on a shaft 4 80 which is journalled in bearings supported by vertical member 1^c and cross member 2^e. This shaft is adapted to be rotated by a gear wheel 5 which in turn is driven by a worm wheel 6 carried on a shaft 7 which also carries 85 a tight and loose pulley on one end thereof as shown at 8 and 9. A suitable drive belt may be used to operatively connect these pulleys with cooperating pulleys attached to a power line shaft. 90

A narrow strip of cardcloth 10 is attached to the periphery of drum 3 near one edge thereof and a feed belt 11 engages with the outside of said drum as shown in Figs. 1 and 2. Belt 11 also passes around pulleys 95 12 and 13 and serves to act as a driving belt for the feed mechanism and the carding belt.

The feeding mechanism comprises an endless belt 17' adapted to run over pulleys 14 and 15. The former is keyed on a shaft 100

adapted to be driven by a belt running over pulleys 18 and 19. Pulley 19 is keyed to shaft 12 which is adapted to be rotated by belt 11 so that belt 11 serves to drive the feeding belt in timed relation to the rotation of drum 3. The leaves to be stemmed are placed on belt 17' with the butt end of their stems engaging gage board 20, as illustrated in Fig. 5. This belt will carry them into engagement with belt 11 carried by revolving drum 3 and a carding belt adapted to cooperate therewith and which will be described hereafter.

A separating wheel 21 is positioned at the end of belt 17' which is adjacent to the drum 3 and the carding belt. It is mounted on a shaft 22 and revolves in a plane parallel to the plane of revolution of the drum but slightly off-set from the edge thereof, as shown in Fig. 5, so that the disc-like wheel will engage the projecting stems of the tobacco leaves and move them from the feed belt 17' to the belt 11 in spaced relation to each other. The separating wheel is equipped on its periphery with curved teeth 23 adapted to engage the projecting stems as shown in Fig. 1. Shaft 22 carries the carding belt so that the separating wheel 21 is revolved in synchronism with the carding belt.

A stationary carding brush 24 (Figs. 1 and 5) cooperates with the separating wheel to aid it in positioning the stems of the leaves in proper relation to each other.

After leaving belt 17' and separator wheel 21 the leaves pass along belt 11 between drum 3 and carding belt 25. This belt is equipped with carding cloth and runs on pulleys 26 and 27 which are mounted on shafts 22 and 28 respectively, journaled in suitable bearings on the frame members. This belt lies in the same plane as the strip of carding cloth 10 mounted on the edge of drum 3, as shown in Figs. 2 and 3, so that the belt and the carding cloth strip 10 readily cooperate, as shown in Fig. 1, for part of the circumference of drum 3. That part of the belt which is in contact with drum 3 is adapted to travel in the same direction as drum 3, as shown by the arrow in Fig. 1.

A discharge belt 30 runs on pulleys 27, 31 and 32 which are mounted on shafts 28, 33 and 34 respectively which in turn are journaled in bearings mounted upon the frame-work of the machine. As shown in Fig. 3 belt 30 travels in the same plane as belt 11 and contacts and cooperates with belt 11 at 36 (Fig. 1) so that leaves traveling along belt 11 will be caught between belts 11 and 30, gently disengaged from the carding cloth, and discharges from the machine. Belt 30 also serves to transmit power from the revolving drum 3 to the pulley 27 upon which carding belt 25 is mounted so that the movement of the latter is synchronized with the

revolutions of drum 3. In Fig. 1 the arrows shown on pulleys 31, 32 and 27 indicate the clockwise direction in which they revolve.

Shaft 40 carries pulley 13 keyed thereto as shown in dotted lines in Fig. 1. Belt 11 runs over pulley 13 and thus serves to drive shaft 40. This shaft also has keyed to it pulley 41 over which carries crossed belt 42 which serves to drive pulley 43 which is keyed to and drives shaft 34 over which discharge belt 30 runs.

The arrangement of shafts, pulleys and belts serves to connect up the revolving drum, the carding belt and the discharge belt, so that they will all operate in timed relation to each other.

Mounted on one end of shaft 40 is a cleaning brush 45 which rotates with shaft 40 in a counter clockwise direction (Fig. 1) and in the same plane as carding cloth strip 10. The bristles of brush 45 contact with the strip 10, as shown in Fig. 1, and act to remove any scrap tobacco which might adhere to the carding cloth.

Shaft 34 has a similar brush mounted thereon and shown at 46. It rotates with shaft 34 and in a plane with carding belt 25 and is so positioned that it brushes off any scrap tobacco which might cling to belt 25.

The stemming means comprises an oscillating arm 50 pivoted on cross-member 2^b at 51 and adapted to be moved toward and away from one edge of revolving drum 3 in a path at right angles to the path of travel of the leaves as they pass between drum 3 and carding belt 25. A grooved cam 52 is adapted to engage a pin 53 (shown in dotted line Fig. 2) attached to arm 50 so that pin 53 will follow the groove cut in cam 52 (shown at 54) as the cam rotates, and thus move arm 50 back and forth. Cam 52 is mounted upon and attached to shaft 55 which is journaled in suitable bearings mounted on the frame. Shaft 55 is rotated by sprocket wheel 56 mounted on one end thereof and adapted to be driven by chain 57 which in turn is driven by a smaller sprocket wheel 58 keyed to shaft 7 which derives its power directly from the tight pulley 8. Inasmuch as the revolving drum 3 and the oscillating arm 50 derive their power from a common shaft, i. e., shaft 7, and as the power transmission in one case is through a worm and wheel and in the other case through a chain and sprocket wheel, there will be no slip and the arm and drum will move in timed relation to each other at all times.

The upper end of arm 50 carries two gripping members 60 and 61. Each of these members comprise a pair of relatively movable jaws pivoted at 64 and connected by a spring 65 mounted so that the longitudinal axis thereof passes from one side of pivot 64 to the other when the jaws are moved relative to each other. The action of the spring is to 130

tend to hold the jaws either open or closed after they are positioned by some outside force. This result is obtained because the end of the spring attached to the movable jaw rotates about point 64' so as to change the direction of pull of the spring from one side of the pivot to the other as the jaws are opened or closed.

A lug 66 extends downwardly from the rear or movable jaw 62 and is rigidly attached thereto. A bracket 67 is secured to the upper end of frame member 1^a and has two stationary arms 68 and 69 positioned so as to intercept lug 66 near each end of its path of travel as it moves toward and away from drum 3. Stationary arm 68 is adapted to contact with lug 66 as oscillating arm 50 nears the end of its stroke farthest from the drum as shown in Fig. 2 and serves to separate jaws 62 and 63. Spring 65 will hold the jaws open as oscillating arm 50 makes its return stroke and until stationary arm 69 contacts with lug 66 and closes the gripper jaws on the butt end of a leaf stem as shown in dotted lines in Fig. 2.

As shown in Fig. 5, gripping member 60 is offset from drum 3 more than gripping member 61 and stationary cam arms 68 and 69 are curved to compensate for this offset and actuate each gripping member at both ends of its stroke. The result of this offset or staggered arrangement of the gripping members is that member 61 will grip the stem and draw it about half way from the leaf, at which point the movable jaw 62 will be opened because lug 66 strikes against stationary cam arm 68. The half protruding stem will then travel along belt 11 until it comes into the path of action of gripping member 60 which will draw the stem the remainder of the way from the web or laminæ of the leaf. If the stem is drawn from the web in one operation of the stemming device the result is often a torn leaf or broken stem because the body of the leaf is travelling at right angles to the direction of pull during this operation. Making this stemming operation a series of short pulls rather than one long pull cures this defect.

Gripping member 61 is equipped with flexible pins or bristles as shown at 70 in Fig. 2. Gripping member 60 is equipped with two insulated rubber strips 71, as shown in Fig. 4.

In operation the leaves to be stemmed are placed upon feed belt 17' so that the ends of their stems contact with gage plate 20, as shown in Fig. 5. The feed belt delivers them to belt 11 so that the body of a leaf falls on the belt while the butt end of the stem projects out through the cardcloth 10. A separating wheel 21 serves to space the leaves in relation to each other and to the stemming means. Part of the body of each leaf passes under carding belt 25 and is gripped between the carding belt and the carding cloth 10

with the end of the stem projecting, as shown in Fig. 5. When a leaf comes opposite to gripper 61 the butt end of the stem is gripped thereby and the stem partly pulled from the web portion, as shown in dotted lines in Fig. 5. Upon release by gripper 61 the leaf travels to a position opposite to gripper 60 which grips the stem upon the next succeeding stroke of arm 50 and when arm 50 moves away from the drum 3 the stem is entirely removed from the web. When lug 66 of gripper 60 contacts with stationary arm 68 and the jaws of the gripper are opened the stem will drop out and may be removed as seen fit. The web of the leaf continues to travel around drum 3 until it passes under discharge belt 30 and is held between belts 11 and 30 which will remove it gently from the carding cloth and discharge it on the left side of the machine, as shown in Fig. 1.

Although I have shown and described one embodiment of my invention it is to be understood that the same is susceptible of various changes, and I reserve the right to make and use such of these as may come within the scope of the appended claims.

What I claim is:

1. In a tobacco stemming machine, a revolving drum a feed belt on the drum and driven thereby at the same linear speed as that of the drum, a travelling belt cooperating therewith, means for feeding tobacco leaves between said drum and said travelling belt in spaced relation to each other, reciprocating means adapted to grip the stem of a tobacco leaf and draw it from the web of the leaf while said web is held between said travelling belt and said drum and being moved along by said feed belt.

2. In a tobacco stemming machine, a revolving drum having a carding belt thereon, a travelling carding belt cooperating therewith, means for feeding tobacco leaves between said carding belts in spaced relation to each other, means adapted to reciprocate at approximately right angles to said drum and in timed relation thereto and to draw the stem of a leaf from the web thereof while said web is held between said carding belts.

3. In a tobacco stemming machine, a revolving drum, a travelling belt cooperating therewith, means for feeding tobacco leaves between said drum and said belt in spaced relation to each other, stemming means comprising an oscillating arm adapted to move in timed relation to said drum and belt, two pairs of jaws carried on said arm and arranged so that one pair will draw a stem of a leaf approximately half way out of the web and the other pair of jaws will draw it the remainder of the way out of the web.

4. In a stemming machine, a revolving drum equipped with a strip of carding cloth near one edge thereof, a travelling carding belt positioned so as to travel and cooperate

with said strip of carding cloth for part of the periphery of said drum, means for feeding leaves between said cooperating drum and belt in spaced relation to each other, and oscillating gripping means adapted to grip the stem of said leaves and draw them from the web thereof.

5. In a stemming machine, a revolving drum, the periphery of which is equipped with a strip of carding cloth along one edge thereof, an endless belt cooperating with an arc of the periphery of said drum and equipped with carding cloth adapted to operate in contact with the carding cloth on said drum, and stemming means comprising a reciprocating gripping means for drawing the stem of a tobacco leaf from the web while it is held between said drum and said belt.

20 6. In a tobacco stemming machine, a revolving drum, a travelling endless belt adapted to cooperate with at least part of the circumference of said drum, spacing means adapted to feed leaves between said drum and belt in spaced relationship to each other, an oscillating arm adapted to move to and from said drum in timed relation thereto, and gripping means on said arm comprising two pairs of jaws mounted side by side and adapted to successively grip a stem and draw it from the web of the leaf.

7. In a tobacco leaf stemming machine, a revolving drum, an endless belt cooperating therewith, means for feeding tobacco leaves between said drum and belt in spaced relation to each other and with the ends of the stem thereof projecting on one side from between said drum and belt, stemming means comprising an arm adapted to oscillate to and from the path of travel of the leaves passing between said drum and belt, a pair of stem gripping means mounted upon said arm, one of said stem gripping means adapted to pull the stem part way from the web of a leaf and the other to pull it the remainder of the way upon the next stroke of said oscillating arm away from said drum and belt.

8. In a tobacco leaf stemming machine, a revolving drum, an endless belt cooperating therewith, means for feeding tobacco leaves between said drum and belt in spaced relation to each other and with the ends of the stem thereof projecting on one side from between said drum and belt, stemming means comprising an oscillating arm, a pair of stem gripping elements each made up of relatively movable jaws and a spring adapted to hold said jaws in a closed or open position, means for opening and closing said jaws at predetermined times.

9. In a stemming machine, feeding means adapted to feed tobacco leaves in spaced relation to each other and to hold the web portion of said leaves with the ends of the stems

protruding from said feeding means, stemming means comprising a plurality of gripping members each adapted to draw the stem only part way from the web of the leaf.

10. In a tobacco leaf stemming machine, feeding means comprising cooperating movable elements adapted to hold the body of a tobacco leaf therebetween with the end of the stem protruding therefrom, stemming means comprising a plurality of stem gripping elements, means for moving said elements toward and away from the path of travel of said leaves as they pass through said feeding means, means for actuating said gripping elements so that each will act on a stem to pull it only part way from the web of the leaf.

11. In a tobacco leaf stemming machine, feeding means comprising cooperating movable elements adapted to hold the body of a tobacco leaf therebetween with the end of the stem protruding therefrom, stemming means comprising an arm adapted to oscillate toward and from said feeding means and in timed relation thereto, a plurality of stem gripping means on said arm adapted to act on a leaf in succession each pulling the stem part way from the web and the last to act on the leaf adapted to remove the stem entirely from the web of the leaf.

12. In a stemming machine, a revolving drum equipped with a strip of carding cloth near one edge thereof, an endless belt adapted to engage with and travel around at least part of the periphery of said drum and to carry the leaves to be stemmed thereupon, a carding belt adapted to cooperate with said strip of carding cloth, feeding means adapted to feed leaves between said carding belt and said strip, stemming means comprising a reciprocating member adapted to grip the stems of the leaves and draw them from the web thereof, and a discharge belt positioned to cooperate with said endless belt to remove the web portion of the leaves from the machine.

13. In a stemming machine, stripping means comprising cooperating movable elements, stemming means comprising a reciprocating member with a plurality of gripping means mounted thereon and adapted to operate upon a leaf in succession to finally remove the stem from the web of the leaf.

14. In a stemming machine, a stripping means comprising movable cooperating members, and stemming means comprising a reciprocating element with a pair of gripping members mounted thereon so as to act in succession upon a leaf, the first to operate upon the leaf being adapted to only partly remove the stem from the web and the second to entirely disengage the stem and web.

15. In a tobacco stemming machine, a revolving drum, lineally moving feed means cooperating therewith, a reciprocating member, a plurality of gripping means mounted

thereon in an offset relation to each other, so as to operate successively upon a stem and draw it from the web of the leaf.

16. In a tobacco stemming machine, a revolving drum, a travelling belt cooperating therewith, means for feeding tobacco leaves between said drum and said belt in spaced relation to each other, gripping means adapted to travel substantially at right angles to the path of travel of said belt and comprising a plurality of offset gripping members adapted to draw the stem from the leaf and each positioned and actuated to perform only part of the complete operation.
17. In a tobacco stemming machine, a revolving drum, a travelling belt cooperating therewith, means for feeding tobacco leaves between said drum and said belt with spaced relation to each other, a reciprocating member adapted to travel at substantially right angles to the path of travel of the leaves passing between said drum and said belt, and a plurality of gripping members mounted on said reciprocating member and offset different distances from said cooperating drum and belt and adapted to operate in succession upon a leaf, each to perform part of the complete operation of drawing the stem from the web portion of the leaf.

30 Signed at Richmond, in the county of Henrico, and State of Virginia this 26th day of October, A.D. 1928.

JOSEPH JEROME CAUDLE.
